METAL FORMING TOOL

Jay W. Joseph, Downers Grove, and Arden L. Van Nest, Oak Park, Ill., assignors to Western Electric Company, Incorporated, New York, N. Y., a corporation of New York

Application March 10, 1939, Serial No. 260,948

3 Claims. (Cl. 140—113)

This invention relates to metal forming tools, and more particularly to a tool for splicing wires by rolling a metallic connecting sleeve into intimate contact with abutting ends of the wires.

5 An object of the invention is to provide a simple, inexpensive and efficient tool of the type above referred to.

One embodiment of the invention contemplates a sleeve rolling tool comprising a pair of 10 cooperating pressure rollers, one of which is segmented to provide two or more separated arcuate surfaces of different lengths for selective cooperation with the other roller to roll connecting sleeves of correspondingly different lengths. An 15 operating hand lever is provided which is quickly reversible to permit convenient manipulation thereof when either of the arcuate surfaces of the segmented roller is in operative relationship with the other roller.

20 Other features and advantages of the invention will become apparent from the following detailed description when read in conjunction with the accompanying drawing, in which

Figs. 1 and 2 are front and side elevational 25 views, respectively, of a sleeve rolling tool embodying the invention;

Fig. 3 is an enlarged front elevational view of 30 a portion of the tool, showing the segmented roller in starting position and a connecting sleeve in position to be engaged by the rollers;

Fig. 4 is a view similar to Fig. 3, but shows the 35 segmented roller in an intermediate position and the connecting sleeve partially rolled, and

Fig. 5 is a fragmentary sectional view on line 5—5 of Fig. 4.

Referring now to the drawing, the sleeve rolling tool illustrated therein comprises a handle member 10 having an enlarged offset end portion 11 to which a pair of stub shafts 12 and 13 are 40 secured in spaced parallel relationship, as best shown in Fig. 5. A pair of cooperating pressure rollers 15 and 16 are rotatably mounted on the shafts 12 and 13, respectively. One of the rollers, preferably the lower one 16, is somewhat 45 larger than the other roller and is segmented, as shown, to provide two arcuate surfaces 17 and 18 separated by flat surfaces 19 and 20. The arcuate surfaces 17 and 18 are of different lengths and are adapted to be selectively brought 50 into operative relation with the upper roller 15 by means of a hand lever 22. This hand lever has a dovetail groove 23 slidably engaging the heads of a pair of diametrically opposed studs 24, 24 attached to the segmented roller, so that the 55 hand lever is quickly reversible to permit con-

venient manipulation thereof when either of the arcuate surfaces of the segmented roller is employed.

The flat surfaces 19 and 20 permit insertion of the wires to be spliced between the two rollers, 5 and also permit withdrawal of the spliced wires from between the rollers without returning the rollers to their starting positions. Thus, when one of the flat surfaces is in position to permit insertion of the wires to be spliced, the other flat 10 surface arrives in position to permit withdrawal of the wires at the completion of the splicing operation. The particular flat surface that is moved into position to permit insertion of the wires to be spliced will, of course, depend upon 15 the arcuate sleeve rolling surface that is selected and this selection depends upon the length of the connecting sleeve that is being used. Since the flat surfaces of the segmented lower roller provide sufficient clearance for insertion and 20 withdrawal of the wires, the upper roller need not have any notched or flat surface but may have a continuous uniform sleeve rolling surface, so that it need not be rotated in synchronism with the lower roller. Therefore, the usual 25 interconnecting gearing between the two rollers is dispensed with, the segmented lower roller is rotated directly by the hand lever, and the upper roller is free to rotate independently of the lower roller. Thus, a simple and inexpensive construc- 30 tion is provided.

The upper roller is preferably provided with two or more annular grooves 26, 26 of different radii for accommodating wire connecting sleeves of different diameters, and the arcuate surfaces 35 of the segmented lower roller are provided with similar grooves 27, 27 for cooperation with the grooves of the upper roller.

The operation of the tool, when employed to splice two wires 28 and 29 by means of a connecting sleeve 30, is as follows:

If the length of the connecting sleeve corresponds to the length of the longer arcuate surface 17 of the segmented lower roller, the lower roller is rotated by hand lever 22 to the position 45 shown in Fig. 3, in which the flat surface 19 is in position to permit insertion of the wires to be spliced. The end portions of the wires, having been inserted in opposite ends of the connecting sleeve, the wires and sleeve are then inserted between the rollers, after which the segmented roller is rotated by hand lever 22, causing the connecting sleeve to be rolled between the upper roller and the arcuate surface 17 of the lower roller, as shown in Fig. 4. At the completion of 50 55

the rolling operation, the other flat surface 20 of the lower roller arrives in position to permit withdrawal of the spliced wires, as explained above. If the length of the connecting sleeve 5 corresponds to the shorter arcuate surface 18 of the lower roller, then the lower roller is first rotated to a position in which the flat surface 20 is in position to permit insertion of the wires, in which case the flat surface 19 would arrive in 10 position to permit withdrawal of the wires after the completion of the rolling operation. When employing the shorter arcuate surface 18, the lower roller will assume the position indicated in broken lines in Fig. 4 at the completion of 15 approximately one-half of the rolling operation.

It is to be understood, of course, that the segmented roller may have more than two arcuate surfaces of different lengths and that more than two sleeve receiving grooves, such as 26 and 27, 20 may be provided in each of the rollers to accommodate connecting sleeves of several different lengths and diameters. Also, other changes and modifications may be made without departing from the spirit and scope of the invention, as 25 expressed in the appended claims.

What is claimed is:

1. A sleeve rolling tool comprising a pair of cooperating pressure rollers, one of which is segmented to provide a plurality of sleeve rolling surfaces of different lengths for selective cooper- 30

ation with the other roller, and a hand lever for rotating said segmented roller, said hand lever being reversible to permit convenient manipulation thereof when any one of said arcuate surfaces of the segmented roller is in operative relation with the other roller. 5

2. A sleeve rolling tool for splicing wires, comprising a pair of cooperating pressure rollers, one of which is segmented to provide spaced flat surfaces and an arcuate sleeve rolling surface there- 10 between for cooperation with the other roller, said arcuate sleeve rolling surface being of a length approximating the length of the sleeve to be rolled, one of said flat surfaces permitting insertion of the wires to be spliced between the 15 two rollers while the other flat surface permits withdrawal of the spliced wires.

3. In a tool for splicing wires by rolling a metallic connecting sleeve into intimate contact with abutting ends of the wires, a pair of co- 20 operating pressure rollers, one of which is segmented to provide a plurality of arcuate sleeve rolling surfaces for selective cooperation with the other roller, and means for rotating the segmented roller to position a selected one of said sleeve rolling surfaces in operative relation to the other roller. 25
